TYPEWRITER RIBBON SPOOL

Ronald D. Dodge, Rochester, N. Y., assignor to
International Business Machines Corporation,
New York, N. Y., a corporation of New York

Application June 23, 1942, Serial No. 448,070

2 Claims. (Cl. 242—124)

This invention relates to typewriting machines. An object of the present invention is to provide an improved typewriter ribbon spool.

An object is to provide a typewriter ribbon spool which is demountable so that it may be permanently associated with the machine and not, as is the usual case, thrown away with the ribbon when the ribbon becomes exhausted of ink.

An object is to provide a ribbon spool which conserves raw materials.

An object is to provide a ribbon spool on which the ribbon, which is already wound upon a suitable core, may be slipped to enable the ribbon spool to be used over and over again and not thrown away as has been customary heretofore.

It has been the practice in the typewriter art to merchandise inking ribbons already wound upon spools which are usually made of sheet metal with the sides of the spools permanently attached to the hub. The machine usually has two of these spools and, in placing a new ribbon in the machine, the old ribbon and the spool on which it has been wound is usually thrown away and the new ribbon on a new similar spool is substituted. The ribbon is then threaded through the machine and attached to the empty spool which is left after the exhausted ribbon is completely wound on the spool thrown away. This is a very wasteful procedure because the ribbon spool thrown away is usually in good condition and could be used many times before becoming sufficiently worn out to warrant throwing it away.

It has been proposed to wind the ribbons on a suitable inexpensive core to which the inner end of the ribbon is attached and make the ribbon spools demountable so that the ribbon end and its core may be slipped upon the hub of the spool and the spool reassembled to permit the spool to be used over and over again until its condition warrants discarding it.

Accordingly an object of the present invention is to provide a demountable or separable ribbon spool which will be capable of being taken apart for the insertion of a new ribbon to avoid the rather messy operation of winding of the ribbon on the spool by hand.

Other objects of the invention will be pointed out in the following description and claims and illustrated in the accompanying drawing, which discloses, by way of example, the principle of the invention and the best mode, which has been contemplated, of applying that principle.

In the drawing:

Fig. 1 is a front view of a ribbon spool constructed according to the teachings of the present invention.

Fig. 2 is a side view of the ribbon spool with the ribbon and its core removed to show the construction of the spool hub.

Fig. 3 is a vertical section through the removable flange of the ribbon spool.

Fig. 4 is an end view of the ribbon core, showing how the ribbon is attached thereto.

Fig. 5 is a side view of the ribbon core.

Fig. 6 is a view of one end of the ribbon.

The ribbon spool comprises two flanges 10 and 11 (Fig. 2) and a central hub 12, the flange 10 being removably attached, while the flange 11 is permanently attached, to the hub 12. These flanges 10 and 11 are both provided with ratchet teeth 10a (Fig. 1). In the well known "Electromatic," ratchet teeth 10a cooperate with the ribbon feed pawls which rotate the ribbon spool to wind the ribbon thereon, the spool being rotated one tooth space for each type bar operation. These ribbon spools may be suitably dimensioned to fit any well known typewriting machine or to fit other machines which employ inking ribbons as a means of inking the type impressions upon the work sheet. Where the ribbon spool is driven through its hub, as by a shaft, it may be necessary in some cases to modify flanges 10 and 11 to provide the necessary keyway or some other means of temporarily fastening the ribbon spool to the shaft which rotates it. No such means are shown herein since the ratchet teeth 10a in the "Electromatic" provide the sole means of rotating the spool which is merely loosely pivotally mounted in the machine in cooperation with the ribbon feed pawls.

The hub 12 is cylindrical and is formed of a single narrow strip of sheet metal bent nearly circular, but is not of sufficient length to form a complete cylinder for a purpose to be made clear hereinafter. The hub 12 may be formed with a prong or tooth 12a which may, in some cases, provide a means of temporarily attaching the end of the ribbon to the spool, according to the procedure adopted in replacing the spool, of which more will be said hereinafter.

The hub 12 is formed with four lugs 12b which are passed through suitable slots in the flange 11 and bent radially outwardly from the center or axis of rotation of the hub 12 to securely hold the flange 11 on the hub 12. The hub 12 is also provided with a plurality of equally spaced lugs 12c which are bent radially inwardly toward the axis of the ribbon spool and the flange 10 is provided with rectangular holes the outer edges of which fit over the outer sides of the lugs 12c so that the flange 10 may be slipped on the hub 12 and will be supported by the lugs 12c with the inside or right hand face of the flange 10 (Fig. 2) abutting against the left hand end of the hub 12, the holes 10b in the flange 10 being large enough to admit the bentover lugs 12c. There are four of the lugs 12c and for the purpose of locking the flange 10 on the hub 12 by means of the lugs 60 there is provided a locking member or rotary

bolt 13 which may take the form of a spider pivotally mounted on a flange 10 by means of a bushing 14 rivetted to member 13 as best shown in Fig. 3. Bushing 14 has a shoulder rotating in a hole in flange 10 and serves as one bearing for rotatably supporting the ribbon spool in the machine.

The member 13 is formed with a cruciform portion 13a to form four locking projections 13b which, when the member is set in the position of Fig. 1, project tightly under the lugs 12c and securely hold the flange 10 on the hub 12. As a means of preventing the member 13 from being too easily turned, owing to the fact that the pivot on flange 10 will ultimately become worn in time and too loose, member 13 is formed with a nicked or notched portion 13c which registers with the grooves formed by suitable stiffening ribs 10c on the flange 10. The member 13 is sufficiently resilient so that the operator of the machine may grasp a finger-piece 13d (Fig. 1) and press the member 13 slightly away from the rib 10c with which the notched portion 13 cooperates and rotate the member 13 counterclockwise (Fig. 1) far enough to disengage the locking projections 13b from the lugs 12c to permit removal of the flange 10. When the new ribbon has been inserted and the flange 10 replaced, the finger-piece 13d may be pushed in a clockwise direction until the notched portion 13c again snaps over the rib 10c.

In order to attach the ribbon 15 to the spool it is contemplated that the ribbon be wound on a suitable core 16 (Figs. 4 and 5) which may take the form of a short piece of fiber or cardboard tubing. Conveniently the ends of the ribbon 15 may be provided with a grommet 17 and the core 16 is formed with an open slot 16a (Fig. 5) which leads to a central circular hole 16b. The grommet 17 is attached to the end of the ribbon and, before winding the ribbon on the hub, at the time the ribbon is manufactured, the portion of the ribbon just to the right (Fig. 6) of the grommet 17 is slipped into the slot 16a and the ribbon bunched at the opening 16b. Slot 16a is made just large enough to receive the ribbon edgewise and opening 16b made just large enough for the bunched part of the ribbon. The ribbon is then wound on the hub 16 and another grommet 17 may be placed on the outer end of the ribbon before packaging the ribbon.

When the operator desires to insert a new ribbon, the old one will be completely wound on one or the other of the two spools in the machine and the outer end of the old ribbon detached from the empty spool. The filled spool with the used ribbon may then be removed from the machine as a unit and the member 13 operated as described above to release the flange 10. The used ribbon may then be slipped off the hub 12 and thrown away in which case the only loss will be the fiber or cardboard bushing 16. The operator will then slip the new ribbon on the hub 12, taking care to see that the portion of the ribbon containing the grommet 17 is aligned with the slot adjacent the prong 12a in pushing the new ribbon upon the hub 12. When the flange 10 is replaced, the grommet 17 will act like a key to prevent the core 15 from turning on the hub 12. The outer end of the new ribbon may then be threaded through the machine in the usual way and the grommeted portion slipped into the empty core 16 which will remain on the empty

spool in the machine. Conveniently two demountable ribbon spools like the one shown in Figs. 1 to 3 may be used and, in attaching the free end of the new ribbon to the empty spool, the same general procedure may be followed as in attaching the inner end of the ribbon to its core and placing the coil of ribbon and its core on the first spool. Conveniently the open end of slot 16a will confront the flange 11 when inserting the ribbon to insure that the free end of the ribbon will not become detached when the flange 10 is replaced on the empty spool.

This method of attaching the ribbon to the spools is much cleaner than using the fingers to push the ribbon down into the space opposite the prong 12a and pulling on the ribbon in an attempt to anchor the ribbon to the prong. However, since the removal of the flange 10 leaves the interior of the hub 12 more accessible, it will be found it is much easier to attach the free end of the new ribbon by the prong 12a than it would be with an ordinary ribbon spool for which the flanges are rigidly attached to the hub. It is quite common to construct typewriter ribbon spools with prongs like 12a for the purpose of anchoring the ribbon to the spool. On account of the close spacing of the flanges it is usually a dirty and difficult task to hook the end of the ribbon over the prong. It is also a very difficult job to remove completely the ink soiling the operator's hands when performing this operation. With the method of attaching the ribbon shown in Figs. 4 to 6, the end of the ribbon may be handled very lightly and merely slipped into the slot 16a in the core 16 and no force is required. Therefore it is possible to dispense with prong 12a if desired, but it may be provided in case it is preferred to use this means of anchoring the ribbon or for use with ribbons which are not provided with the core 16.

While there have been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A ribbon spool for typewriting and other office machines, comprising a pair of spool flanges, a hub rigidly secured to one of said flanges and provided with radially extending locking lugs equally spaced from the axis of the hub and a locking member rotatably mounted on the other flange concentric with the axis of the hub and having a plurality of locking projections rotatably movable under said lugs to lock the other flange to the hub.

2. A ribbon spool for a typewriting and like machine, comprising two flanges, a hub portion secured to one of said flanges and having a plurality of equally spaced locking lugs, and a rotary locking spider pivotally mounted on and concentric with the axis of rotation of the second flange and having a plurality of locking arms designed to move underneath said locking lugs when the locking spider is rotated, and releasable means to hold said locking spider in locking position.
